PAPER FEED MECHANISM

Arthur Pentecost, Upper Montclair, N. J., and
John L. Sterling, Bellerose, N. Y., assignors
to Remington Rand Inc., New York, N. Y., a
corporation of Delaware

Application January 23, 1948, Serial No. 3,956

15 Claims. (Cl. 197—133)

1

This invention relates to paper feeding, and more particularly to the feed of paper past a printing position in business machines.

A large portion of the printing done on business machines is on forms, such as bills, ledger sheets, report forms, checks, etc. It has become the practice to print these forms on webs of paper which are fed through the machine. It is obvious that the length and layout of each particular form will vary slightly, and in many instances a great deal, especially as to length. For instance, bill forms may range anywhere from three and one half inches in length to twelve or fourteen inches; also, checks may vary from two and three quarter inches to three and one half inches. It is, therefore, obvious that a paper feed which is adaptable to feed a three and one half inch form would not be suitable for one, say, of seven and one half inches.

Also, it is desirable, under certain conditions, to print certain data, such as totals, on or near the bottom of any form whether it be short or long. Each variation as to length of form necessitates a change or adjustment of the feeding mechanism, often resulting in a complicated device which is not only expensive but difficult to maintain in working order.

Regardless of the length of a bill form, there are many instances where the number of items relating to one transaction is greater than the number of lines in the body of the form. It is, therefore, necessary to print the remainder of said items on the next form. Most bill forms have an address block in which it is not desirable to print items, therefore, it is necessary that the paper feed be constituted to skip over the address block and stop the paper on the first line of the body of the bill.

A further difficulty often arises in feed mechanisms for web paper, i. e., the paper becomes fouled with the inking ribbon upon being initially inserted in the machine.

It is, therefore, the principal object of this invention to provide a feeding mechanism which will feed forms of any length or layout to the printing line of a business machine.

A further object is to provide a feed which is simple and easy for the operator to adjust.

Another object is to provide a feeding device into which the paper may be easily introduced without fear of fouling the ribbon.

The principal feature of the invention resides in the provision of a control tape, perforated in accordance with the printed form to be used, which controls electrical means whereby the

2

paper is fed under the joint control of the machine and the tape.

A further feature is the provision of driving means, separate from that of the business machine, which is controlled by both the tape and machine functions.

Another feature is that the paper feed mechanism is pivotally mounted on the business machine in such manner that it may be swung clear of the machine to permit easy accessibility while starting a web of forms through the machine.

A more clear conception of the operation, construction and further objects of the invention may be had from the following specification when read in the light of the drawing, in which

Fig. 1 is a cross section through a tabulator to show the invention thereon in a position to receive paper;

Fig. 2 is a side view of an embodiment of the invention;

Fig. 3 is an opposite side view of Fig. 2 with a portion of the frame removed to show the drive mechanism;

Fig. 4 is a plan view showing the drive and certain controls;

Fig. 5 is a rear view of the mechanism showing the ribbon reversing mechanism and certain of the drives;

Fig. 6 is an isometric showing of the ribbon feed mechanism;

Fig. 7 is a cross section taken along line 7—7 of Fig. 3;

Fig. 8 shows the drives for the line space and printing platen, as well as the location of the contacts controlled by functions of the tabulator;

Fig. 9 is an isometric view of the print platen actuating mechanism;

Fig. 10 is a diagram of the path of paper travel;

Fig. 11 is a detail view of the paper drive in Stop position;

Fig. 12 is a detail cross section on line 12—12 of Fig. 11 showing the contact breaker arm controlled by the motor;

Fig. 13 shows a form adapted to be printed by the machine and its associated control tape; and

Fig. 14 is a diagram of the electrical control circuit.

The preferred embodiment of the invention is shown on a record controlled tabulating machine, such as that disclosed and described in Patent 2,381,361 to John Mueller. It may be well at this point to call attention to the fact that feeds such as single, double, and triple spacing are under control of the tabulator as described in the above patent, but long feeds of the paper,

such as those over titles and in compensating, are controlled by the present invention. Certain conditions of long feed are controlled by functions of the machine, such as total taking, change of designation, and printing. These functions will be described hereinafter in the operation of the invention.

In view of the fact that the tabulator is fully disclosed and described in the above mentioned patent, only those parts necessary for an understanding of the invention will be described, using the same reference characters as in said patent. Referring to Fig. 1, cards are fed from magazine 120 located between the base frames 100, by a picker knife 118 to the feed rolls 108 which convey the card to a sensing chamber 122 where the perforations therein are sensed by sensing pins 138 which pass through the card, raising lock pins 146. Located between the upper side frames 101 is a translator 238 carrying wires 240 which transmit the motion of pins 146 to the permutation slides 235 of a decoding unit. The slides 235 are positioned in accordance with the coded data and set stops 225 which, in turn, cooperate with a stepped heel 205 on a type rack 195. The type racks are cyclically released and rise under spring tension to position the type bars 197.

Each row of lock pins 146 controls a slide 420 which is actuated upon a change of data occurring in that column, and controls a total taking mechanism described in the above patent, which, in turn, controls a total shaft 426 which shaft controls the taking of totals from the accumulators 20.

Paper feed carriage

The embodiment of the invention comprises a carriage in which webs of paper may be fed either by means of a line spacing mechanism operated by the tabulator, or a long feed device driven by a separate motor under control of a perforated tape. The carriage comprises two side frames 10 (Figs. 3, 4, and 5) secured together by a cross member 11 and two tie rods 12. The carriage is pivotally mounted with relation to the tabulator on a U shaped bracket 14 which is slidably mounted in a block 15 secured to the upper side frame 101 of the tabulator. Bars 16, fastened in any well known manner, hold the bracket 14 in the block 15. The bracket 14 is provided with trunnions for a shaft 17 journaled in the side frames 10 of the carriage. The shaft 17 acts as a pivot about which the carriage may be rocked from the position of Fig. 2 to that of Fig. 1, to permit easy threading of a new web of paper or a new ribbon into place. The block 15 is threaded to accommodate a threaded shaft 18 which co-acts with threaded bosses on the side frames 10. A handle 21 on shaft 18 permits the carriage to be adjusted laterally with respect to the type bars 197.

Mounted in each frame 10 is a knurled set screw 22, with a locking nut thereon (Fig. 3), which acts as a feed unit supporting member when said unit is in operating position, and provides a means for adjusting the clearance between the paper feed unit and the tabulator frame. A latch 23 secured to a cross shaft 24 mounted on the tabulator frame engages a cross rod 25, secured between frames 10, which locks and retains the paper feed unit in operative position. A hand lever 26 secured to shaft 24 is provided for rocking latch 23 to ineffective position. Also mounted on frame 10 is a latch 27 adapted

to engage bar 16 (Fig. 1) to support said unit when said unit is in open or inoperative position. Latch 27, which is centrally pivoted, is urged into engagement with bar 16 by spring 28 and remains in that position until released. To accomplish unlatching, a slight pressure by the operator, extending spring 28, moves latch 27 away from bar 16, permitting the unit to be urged into its closed or operative position.

10 In order to lift the paper feed unit easily to its inoperative position and to prevent slamming when the unit is lowered, two springs 30 are provided (Figs. 3 and 4) wound on each end of the shaft 17. The springs 30 are compressed by pins 15 31 mounted on the frames 10 and the brackets 14 so that the springs have a tendency to lift the paper feed unit away from the brackets 14 and the machine frame.

15 Two pairs of feed rolls 32 and 33 are provided, 20 each of which has pins 34 in the periphery thereof adapted to engage perforations in the margin of the web of paper 29 to be fed. As seen in Fig. 10 the paper 29 is passed around the upper periphery of the feed rolls 32, around the roll 35, 25 past the printing platen 36, around free roll 37 and then back over the upper periphery of the feed rolls 33. The feed rolls 32 and 33 are drum shaped and are adjustable laterally of the carriage to accommodate any width of paper, as 30 will be described later. Each roll 32 or 33 is fastened to its respective drive shaft by a set screw in the hub thereof. Each of the feed rolls is provided with a pressure roll 38 which is grooved to straddle pins 34 and is adapted to 35 maintain the paper in contact with the said pins. The pressure rolls 38 are carried on arms 40 (Fig. 5) pivotally mounted in a bracket 41 supported on the drive shafts 17 and 42. A tension spring 43 wrapped around a central pivot 44 for 40 arms 40 acts on pins 45 in each arm to tension the pressure rolls 38 against their respective feed rolls. Rolls 35 and 37 are also provided with pressure rolls 39. Each roll 32 or 33 is rigidly secured to its respective drive shaft 42 or 17 by 45 a set screw, and a loosening of the set screws will permit sliding of the wheels to the desired distance from the central guide discs 46.

50 While the brackets 41 are free on the shafts, the grooves in the pressure rolls 38, engaging the pins 34 in the rolls 32 or 33, tend to maintain the pressure rolls in correct alignment with their respective feed rolls.

55 Feed rolls 32 and 33 are driven from two sources, one the line spacing mechanism of the tabulator and the other an independent motor. Secured to drive shaft 17 or feed roll 33 is a miter gear 50, which meshes with a miter gear 51 secured to one end of a stub shaft 52 journaled in the right hand carriage frame 10. Secured to the other end of shaft 52 is a miter gear 53, which meshes with a miter gear 54 secured to drive shaft 42 for feed roll 32. The 60 ratio of said gears is such that both feed rolls rotate at the same peripheral speed. Journaled in bearings on the side frame 10 is a shaft 55, to one end of which is secured a miter gear 56 meshing with miter gear 54. On the other end of shaft 55 is secured a miter gear 57 meshing with miter gear 58 secured to a shaft 60 on which roller 35 is free to rotate. The shaft 60 is similar to a standard typewriter platen shaft, in that it is provided with the usual positioning knobs 47 and line spacing mechanism.

70 The line space actuating mechanism (as shown in Fig. 8) comprises a cam 732, mounted on shaft

184, which cooperates with a follower roller 131 mounted on bell-crank 730 pivoted on a stud 702. Pivoted to the other end of bell-crank 730 is a link 728 which is, in turn, pivotally secured to arm 726 fast on shaft 727 journaled in the side frame 101. Also secured to shaft 727 is arm 61 having a pin therein that is engageable with electrical contacts for controlling the operating circuit. A description of the electrical circuit containing said contacts will be given herein-after. Arm 726 also carries a roller 725 that co-acts with bail 63 carried on arms 64 journaled on shaft 65. Pivoted to arm 64 is one end of link 66, the other end of which is pivotally secured to one corner of a triangular plate 67. To another corner of plate 67 is pivoted link 68. Secured to the third corner of plate 67 is one end of a strong spring 69, the other end of which is secured to a stud in frame 10. Said spring urges plate 67 counter-clockwise. Link 68 is secured to drive a pawl 70 cooperating with a ratchet 71 secured to shaft 60. The high portion of cam 732 will rock bell-crank 730 counter-clockwise, raising roller 725 through link 728 to rock bail arms 64 which, in turn, will rock plate 67 clockwise through link 66, thus pushing link 68 to the left (Fig. 8) and rotating ratchet 71 clockwise. This rotation is transmitted to feed roll drive shaft 60 which, in turn, drives feed rolls 32 and 33 through the gear train 58, 57 (Figs. 2 and 4), shaft 55, gears 56, 54, 53, shaft 52, and gears 51 and 50. It will be noted that the arrangement of the above gear train is such that clockwise rotation of shaft 60 by ratchet 71 results in clockwise rotation of feed roll 32 and counter-clockwise rotation of feed roll 33.

Print platen actuating mechanism

The printing platen actuating mechanism is operated substantially in the same manner as that described in Patent 2,381,361, and will be but briefly described herein, using reference characters, for old parts, identical with those in the patent. On the left hand side of the tabulator (as shown in Fig. 8), a lever 703 pivotally mounted on a shaft 704 has a forwardly extending arm to which is connected a pull link 709, the lower end of said link being connected to lever 706 which is pivotally mounted on a stud 702, and having thereon a follower roller 107. Said roller engages with a cam 708 secured on a shaft 104. Means are provided that co-act with the lever 703 to prevent platen movement on non printing cycles, and are identical to those shown in the cited patent and, therefore, will not be recited herein. Lever 703, through roller 105, presses against bail 73 supported by arms 74 fast on shaft 65. Also secured to shaft 65 are arms 76 that are pivoted to ribbon and print platen supporting arms 75 (see Fig. 9). Said arms are slidably supported on side frame pieces 10 by pin and slot connections 78, 79. The arms 75 have a bent-over portion (Fig. 9) which tends to hold the paper away from the platen so that when the arms 75 are reciprocated, bringing the platen into printing position as will be presently described, the slack in the paper will be taken up and thus prevent tearing of the paper. Journaled in arms 75 is a printing platen 36. This mechanism, when operated, moves platen 36 and the paper thereon into printing position, in the following manner: Roller 107 riding on the high dwell of cam 708 rocks lever 706 counter-clockwise, pulling link 709 downwardly which, in turn, rocks lever 703 counter-

clockwise, thereby raising bail 73, and through arms 74 and 76 moves arms 75 and platen 36 rearwardly. Springs 77, which are fastened at one end to arms 75 and at the other to pins 78 secured in side frame 10, are provided to move the printing platen 36 toward the type 197 to effect printing. Follower roller 107, upon entering the low dwell of cam 708, allows springs 77 to move arms 75 and platen 36 forward. The arms 75 press against ribbon 80, stretching same to overcome the normal sagging tendency. Previous to this invention, it was found that the type sector bars ascending and descending had a tendency to catch and tear or otherwise damage the ribbon. This feature of the invention, the forward movement of the platen 36 with arms 75 extending the ribbon toward the type 197 only when the type sector bars 195 are positioned for printing and the return of said arms and ribbon immediately after printing, eliminates the undesirable mutilation of the ribbon.

Ribbon feed mechanism

25 A bracket 81, mounted on the outer side of each of the upper side frames 101 of the tabulator and immediately below the paper feed unit, has a mounting stud 82 for a ribbon spool 83 or 84 secured therein. The brackets 81 also support their related drive mechanisms, as shown in Figs. 2, 5, and 6. A link 85 pivotally secured to a rotating disc 86 fast on the tabulator front head drive shaft 185 is connected to a stud 87 mounted on arm 88 free on a shaft 90. Also pivoted on stud 87 is a latching link 91 having a pin 92 thereon that co-acts with detent notches in a latching member 93 that is pivoted on a stud 95 mounted on the bracket 81. Secured to latching plate 93 is an arm 94 having a protrusion 96 formed at its extremity which is adapted to be engaged by a spring pressed latch 97 pivoted on the bracket 81. The latch 97 is provided with a ribbon engaging pin 98. Also attached to arm 94 is a link 102 connected to an arm 103 fast on shaft 90. Mounted on a stud 105 in the other bracket 81 is an arm 104. Attached to arm 104 is a link 106 which, in turn, is attached to an arm 107 fast on shaft 90. A blocking member 110 is pivoted on a stud 111 mounted in the bracket 81 and has secured thereon a ribbon engaging pin 112.

55 A driving mechanism for rotating each of the ribbon spools 83 or 84 is provided which comprises a ratchet wheel 113 and a pawl 114. The pawl 114 is carried on an arm 115 pivoted on the spool spindle 82 on which the ratchet wheel 113 is pivotally mounted. The ratchet wheel 113 is held on the spindle 82 by a spring and washer as shown in Figs. 6 and 7 which are drawn against the wheel 113 by a nut shown in Fig. 7. The arm 115 is provided with a roller 116 which is held in contact with either arm 94 or 104 by spring 117. Arms 94 or 104 are rocked once each machine cycle by shaft 90 which is, in turn, rocked by link 85 acting through arm 88, link 91, detent plate 93, arm 94, and link 102, to arm 103, fast on the shaft.

70 In the position shown in Fig. 6, the ribbon which is fed around the roller 122 and through the guides 121 has nearly filled the left hand spool 83, permitting latch 97 to engage and lock arm 94 from rocking. On the next reciprocation of link 85, the arm 94 and detent plate 93 will be held, and the link 91 will move the pin 92 therein from one detent notch to the other, the

7 roller 116 being at this time in contact with the stationarily held arm 94 as illustrated in Fig. 6, and the arm 115 and the pawl 114 occupying their normal or idle positions wherein the pawl is rocked out of engagement with the ratchet wheel 113 by the engagement of a tail on said pawl with the stop pin projecting from the bracket 81 as also illustrated in Fig. 6. On the return or counter-clockwise reciprocation of link 85, the arm 94 will be rocked counter-clockwise away from roller 116 and arm 104 will actuate the ratchet arm 115 of the drive of the right hand spool 34. From this time on, arm 104 will be effective until the right hand spool is filled. Under this condition, the nose of blocking arm 140, 15 which carries the ribbon sensing pin 142, will be rocked into the path of the arm 104. This will prevent the arm 104 from being rocked the full feeding distance and the pin 92 in arm 94 will snap into the first notch of plate 93, thus making 20 arm 94 effective and arm 104 ineffective.

High speed paper drive actuating mechanism

Secured to the right hand frame 10 is a bracket 25 123 (Figs. 3, 4, and 5) on which is mounted a second bracket 124. Pivotally mounted in frame 10 and bracket 124 is a motor 125 which has secured to its armature shaft 126 a worm 127 adapted to co-act with the worm wheel 128 secured to shaft 42. A toothed wheel 130 is also secured to shaft 42 and is engageable with a toothed braking arm 131, pivotally mounted on a bracket 132, which is secured to motor 125. Braking arm 131 is formed of a plurality of toothed plates the first of which has a turned over lug 133 engaging bracket 132 and is held against said bracket by a spring 134. The engagement or disengagement of worm 127 with worm wheel 128 and braking arm 131 with wheel 130 is controlled by means of an arm 135 mounted on motor 125 and extending forwardly therefrom.

The rocking of motor 125 is controlled by two solenoids 136 and 137. The plunger 138 of the solenoid 136 passes through a slot in arm 135 and is adjusted in relation thereto by lock nuts 141. A latch 140, pivoted on a stud 142 in the frame 10, is adapted to cooperate with the arm 135 of motor 125. The latch 140 is formed with a horizontal arm having a slot therein for accommodating the plunger 143 of solenoid 137, said plunger being provided with an adjusting lock nut 144. A contact breaker arm 145 (shown in Figs. 3 and 12) is slidably mounted on an upright arm 147 secured to the bracket 123. It is urged downwardly by light spring 149 connected between a pin on the bracket and a pin on the arm. The bottom of breaker arm 145 is provided with a contact cooperating with a spring contact 150 also mounted on, but insulated from, bracket 123. When solenoid 136 is energized, as will be explained hereinafter, the arm 135 is drawn down by plunger 138 into locking engagement with latch 140. The rocking of arm 135 rocks motor 125, disengaging worm 127 from worm wheel 128 and engaging braking arm 131 with serrated wheel 130.

The adjustment of arm 135 on motor 125 with relation to latch 140 is such that when solenoid 136 is energized the arm 135 is depressed until motor 125 is rocked a sufficient distance to bring the teeth of braking arm 131 into mesh with toothed wheel 130, thus stopping the rotation of shaft 42, and, consequently, the feed rolls 32 and 33, since worm 127 and worm wheel 128 have been disengaged. The braking arm 131, being

5 spring connected to the bracket 132, permits the positive engagement with wheel 130, and also permits a certain amount of overthrow in rocking the motor. The arm 135 snaps past latch 140 and lowers arm 145, breaking contact 150 (Fig. 11), which immediately opens the circuit to the solenoid 136, thus permitting plunger 138 to rise under the tension of spring 151 until arm 135 is caught by the latch 140. In this position the motor has rocked clockwise through a sufficient arc to disengage braking arm 131 from toothed wheel 130, but not sufficient to engage worm 127 and worm wheel 128. The paper feed is thus placed under control of the line spacing mechanism.

10 When the control tape calls for a long feed, the solenoid 137 is energized, rocking latch 140 clockwise, thus releasing arm 135 and permitting the motor 125 to rock counter-clockwise (Fig. 3) under the influence of spring 151 and the weight of the worm. This rocking brings worm 127 and worm wheel 128 into mesh, thus starting the long feed through rolls 32 and 33.

Control tape

20 As has been noted above, the paper web is fed either by the line spacing mechanism of the tabulator, or by the long feed device under control of a perforated tape. The tape 155 is similar to that used in telegraph transmitters, in that it has a line of drive holes in the center thereof and may be of any good insulating material. Control perforations are located in accordance with the operation to be performed, and in alignment with the position at which that operation is to occur in relation to the form being fed. In 25 Fig. 13 is shown a bill form 156 on which it is desired to print a name and address in the blank space at the top of the form, and then print items, the total of which is to be printed below said items. After printing the total it is desired that the paper be fed to the first line of the address block and stopped, regardless of the line on which the total was printed. If, however, a 30 total was not taken within the body of one bill form, it is desired that the paper be fed over the address block and stopped on the first line of the body of the next bill.

35 There are four lines of control perforations in the tape for performing these operations, one (160) for starting the long feed, i. e., engaging worm 127 and worm wheel 128, two (161) for stopping the feed if a total has not been taken within the body of the bill, i. e., disengaging worm 162 and worm wheel 128, three (162) for controlling the stopping circuits, and four (163) for stopping the feed if a total has been taken within the body of the bill.

40 In view of the fact that the printing on a particular web of forms is repeated over and over, the tape 155 is formed in a loop which is fed in synchronism with the web.

Tape feed mechanism

45 65 A drum 157 of similar diameter to drums 32 and 33 is secured to the end of drive shaft 42 and has pins 158 in the periphery thereof for engagement with the drive perforations in the control tape. The drum is of suitable conductive material and is insulated from the shaft 42. A brush 164 bearing on the face thereof carries the electric circuit through the drum. A second drum 165 is journaled on an arm 166 and located beneath drum 157. The arm 166 is pivotally mounted on frame 10, said arm being urged coun-

ter-clockwise gravitationally to provide tension between said drums when tape 155 is supported thereon.

An arm 167 is pivoted on a stud 168 in bracket 124 and supports five insulated contact brushes 164, 170, 171, 172, and 173, which are urged counter-clockwise against drum 157 by the camming action of a lip 174 formed on arm 167 and a follower roller on an arm 175 journaled to bracket 124 and urged counter-clockwise by spring 176. Said lip and arm also comprise a latching means whereby brush supporting arm 167 may be held away from drum 166 and retained in that position so as to facilitate the positioning of tape 155 on the drums 157 and 165.

The operator, in setting the carriage at the beginning of a printing operation, rocks handle 26 counter-clockwise (Fig. 3), thus unlatching the carriage and permitting it to swing about shaft 17 to the position of Fig. 1. In this position the web may be fed around the rolls as indicated in Fig. 10. The latch 27, which has been holding the carriage in position, is then tripped and the carriage closed against the action of spring 30 until the latch 23 engages the rod 25. By using the knobs 47 the paper may be positioned to the correct alignment for the start of printing. The paper can then be aligned laterally by use of the crank 21 which will shift the entire carriage with respect to the type 197.

The tape 155 is then positioned on the drum 157 with an indicator line 177 in alignment with an indicator 178. The line 177 is a reference line from which all control perforations are made, thus said perforations must be in alignment with the positions in which certain operations are to occur with respect to the particular form being used.

Electrical control circuits

Several electrical circuits in conjunction with mechanical means are employed to control the various paper feeding operations, the general aim being the regulation of the long or rapid paper feeding mechanism and, more specifically, the engaging and disengaging of motor 125 with its associated mechanism. The primary electrical circuit, with reference to Fig. 14, herein employed, shows an alternating current source and a rectified secondary source being used to furnish the potential necessary for operating the various solenoids and relays. Although this method is presently employed, other means may be substituted with the same results.

In view of the fact that certain machine operations, such as printing, change of designation, total taking, and the like, are used for controlling certain functions of the electric circuit, a plurality of contacts 180, 181, 182, 183, and 184 are provided. Each of the above contacts is provided with a bridging switch, by means of which said contacts may be cut in and out of circuit in accordance with the requirements of the form being fed.

In the example to be described, i. e., the form 156 of Fig. 13, contact 180, which is associated with the print mechanism (see Fig. 8), and contact 181, which is actuated by the total shaft 426, are used, therefore, their associated bridging switches are shown open and the remainder closed.

In operation, when the brush 173 enters the first control hole 163, a circuit is closed from positive conductor 186, conductor 187, brush 164, drum 157, through control hole 163, brush 173, over conductor 188, the outer break contact of

relay A, conductor 189, through the winding of Stop solenoid 136, through contact 150, to negative conductor 190, thus operating the Stop solenoid 136 to rock motor 125, thus disengaging the worm drive. A parallel circuit is closed from positive conductor 186, conductor 187, brush 164, drum 157, through control hole 163, brush 173, over conductor 188, through the outer break contacts of relay A, conductor 191, winding of relay C, conductor 192 to negative conductor 190, operating relay C, which opens any locking circuits previously established for relays A and B. The position of hole 163 with relation to the form 156 is such that the long feed stops on the first line 15 of the address block. The machine line space mechanism now takes over the feeding of the paper which is fed for the three lines of the address, and on the third line, a control hole in the last card of the address group causes a double line spacing of the paper over the form line to the next printing line, which is the first item line. This brings control perforation 161 in the tape under brush 171, but due to the fact that relay A has not been operated at this time no circuit will be closed to the Stop magnet 136.

The tabulator continues to print and line space and upon reaching hole 162 in the control tape, a circuit will close from positive conductor 186, conductor 187, brush 164, drum 157, through hole 162, to brush 172, conductor 193, through winding of relay A, over conductors 194, 192 to negative conductor 190, thus operating relay A. Relay A is then locked up over a circuit from negative conductor 190, conductors 192 and 194, through 30 the winding and inner make contacts thereof, inner break contact of relay B, and break contact of relay C, over conductors 196 and 198 to positive conductor 186, thus holding relay A operated under control of relays B and C, and transferring 35 the circuit for the Stop solenoid 136 from brush 173 to brush 171.

This circuit having been established, the machine continues to print items until such time as the total shaft 426 is rocked to take a total, closing contacts 181. This has no effect other than to prepare a circuit, as no operation of the long feed is desired until the printing of the total is completed. The operation of printing closes contact 180 which then completes a circuit from 45 positive conductor 186, contacts 180 and 181, through cut out switches for contacts 182, 183 and 184, conductor 200, through winding of relay B, over conductors 201 and 192 to negative conductor 190, thus operating relay B, and opening 50 the locking circuit for relay A, which releases again, placing the Stop solenoid 136 under control of brush 173. The operation of relay B also closes, through its outer make contact, a circuit from positive conductor 186, conductors 198, outer 55 make contact of relay B, conductors 202 and 203, through the winding of the Go solenoid 137, over conductor 192, to negative conductor 190, thus rocking latch 140 to permit the rocking motor 125 to engage worm 127 and worm wheel 128 to 60 feed the paper to a point opposite hole 163 in the control tape. Hole 163 closes a circuit from positive conductor 186, conductor 187, brush 164, drum 157, through hole 163, brush 173, conductor 188, outer break contact of relay A (which, as 65 will be recalled, was released by the operation of relay B), conductor 189, through the winding of the Stop solenoid 136, through contacts 150 to negative conductor 190, thus disengaging the worm drive at the first line of the next heading 70 group, thereby allowing the machine to take over

single line spacing until hole 161 passes under brush 171. However, since hole 161 is one of the controls for the Stop solenoid 136, it is, at this time, ineffective as relay A is normal, a total having been taken in the previous form. Items are printed and the tape progresses to control hole 162. A circuit is then established, the same as that previously described, resulting in relay A being operated and its associated locking circuit closed, holding it operated. The printing of items is continued until control hole 160, which is opposite the last line of the form, makes contact with brush 170 which closes a circuit from positive conductor 186, conductor 187, brush 164, drum 157, through hole 160 to brush 170, over conductor 203, through the winding of the Go solenoid 137 to negative conductor 190, thus energizing the Go solenoid and engaging the worm drive 127, 128 which feeds the paper to the first item line of the next group, i.e., control hole 161. Since relay A is energized, control hole 163, passing under brush 173, was ineffective as the circuit therefrom passes through a break or open contact. Control hole 161 establishes a circuit from positive conductor 186, conductor 187, brush 164, drum 157, through hole 161, brush 171, conductor 204, outer make contacts of relay A, over conductor 189, through the winding of the Stop solenoid 136 through contacts 150 to negative conductor 190, thus energizing the Stop solenoid and disengaging the worm drive 127, 128, stopping the web at the first item line after skipping the address block and permitting the tabulator to resume normal line spacing operation. The item printing carries control hole 162 under brush 172, but since relay A is in a locked position, control hole 162 is ineffective in this present instance.

It is obvious from the above example that any type of form may be fed through the tabulator, providing the correct combination of control holes are entered in the tape 155 and in the correct relation with the form to be fed. For instance, if a web of checks is to be fed, on each of which checks only one line of printing is desired, i.e., the payee's name and the amount, only one control hole is required. This control hole 163 controls the Stop solenoid 136. If all the cut out switches, except that associated with print contact 180, are closed, the operation would be as follows: The tabulator prints the payee's name and amount on the check, closing the contact 180 which actuates relay B, closing the circuit for operating the Go solenoid 137 which engages the worm drive 127, 128 and feeds the web until the control hole 163, which is opposite the printing line, closes the circuit for the Stop solenoid 136, disengaging the worm drive 127, 128, thus holding the paper for the next printing operation.

What we claim as new, and desire to secure by Letters Patent, is:

1. In a machine of the class described for feeding a continuous web of paper, a plurality of feeding drums, means for driving said drums, means for engaging said driving means with said drums, means for disengaging said driving means from said drums, a latch for holding said driving means normally ineffective, a prepunched endless tape, means for sensing the perforations in said tape, and means under control of said sensing means for selectively operating said latch, and said engaging and disengaging means.

2. In a tabulator of the class described, the combination of a paper carriage, means for laterally positioning said carriage, a latch for

retaining said carriage in a printing position, means for manually releasing said latch, a spring for tilting said carriage away from printing position to permit insertion of said web, a second latch for holding said carriage in said tilted position, a line space mechanism for feeding a web line by line past a printing position, a normally ineffective long feeding means, a pre-punched tape, means for feeding said tape in synchronism with said web, means for sensing the perforations in said tape, and means under control of said sensing means for rendering said long feeding means effective.

3. In a machine of the class described, a plurality of feeding means for feeding a continuous web of paper past a printing position, a driving means associated with said feeding means, a driving medium under control of said machine for actuating said driving means for feeding said web line by line, a second driving medium, a pre-punched tape, means under control of said tape for engaging said second driving medium and driving means to effect a long feed, and means under control of said tape for disengaging said second driving medium and driving means at a predetermined line position on the web.

4. In a machine of the class described, a plurality of feeding means for feeding a continuous web of paper past a printing position, a driving means associated with said feeding means, a driving medium under control of said machine for actuating said driving means for feeding said web line by line, a second driving medium, a pre-punched endless tape, including a plurality of perforations differentially disposed in accordance with predetermined line positions on said web, a circuit under control of certain of the perforations of said tape for engaging said second driving medium and driving means to effect a long feed, and a second circuit under control of certain other perforations of said tape for disengaging said second driving medium and driving means at a predetermined line position on said web.

5. In a machine of the class described, a plurality of feeding drums for feeding a continuous web of paper past a printing position, a gear train associated with said feeding drums, a cam actuated link under control of said machine for actuating said gear train for feeding said web line by line, a continuously running motor, a pre-punched endless tape, means under control of said tape for engaging said motor and gear train to effect a long feed operation, and means under control of said tape for disengaging said motor from said gear train at a predetermined line position on the web.

6. In a machine of the class described, a plurality of feeding means for feeding a continuous web of paper past a printing position, a driving means associated with said feeding means, a driving medium under control of said machine for actuating said driving means for feeding said web line by line, a second driving medium, a pre-punched tape, means under control of said tape including a latch for holding said second driving medium disengaged from said driving means, and means for actuating said latch under control of said tape for engaging said second driving medium and driving means at a predetermined line position on the web to effect a long feed.

7. In a machine of the class described, a plurality of feeding means for feeding a continuous web of paper past a printing position, a driving means associated with said feeding means, a driv-

ing medium under control of said machine for actuating said driving means for feeding said web line by line, a second driving medium, a pre-punched endless tape, a latch for holding said driving medium ineffective, a solenoid under control of said tape for releasing said latch to permit engagement of said second driving medium and driving means to effect a long feed, and a second solenoid under control of said tape for disengaging said second driving medium and driving means at a predetermined line position on the web.

8. In a tabulator of the class described, the combination of a paper carriage, means for laterally positioning said carriage, a latch for retaining said carriage in a printing position, means for manually releasing said latch, a spring for tilting said carriage away from printing position, a second latch for holding said carriage in said tilted position to permit insertion of said web, a plurality of feed drums for feeding a continuous web of paper past a printing position, a line spacing mechanism for feeding said web line by line, a cam actuated driving link under control of said tabulator for actuating said line space mechanism, a gear train associated with said line space mechanism, a pre-punched tape fed by said gear train in synchronism with said web, means for sensing the perforations in said tape, a continuously running motor, a solenoid under control of said sensing means for rocking said motor into engagement with said gear train to effect a long feed of said web, a second solenoid under control of said sensing means for rocking said motor out of engagement with said gear train to effect the stopping of said web at a predetermined position, and a brake for concurrently stopping said gear train upon disengagement of said motor.

9. In a tabulator of the class described, a plurality of feeding means for feeding a continuous web of paper past a printing position, a line spacing mechanism for feeding said web line by line, a driving medium under control of said tabulator for actuating said line space mechanism, a driving means associated with said line space mechanism, a pre-punched tape fed by said driving means in synchronism with said web, means for sensing the perforations in said tape, a second driving medium, means under control of said sensing means for engaging said second driving medium with said driving means to effect a long feed of said web, means under control of said sensing means for disengaging said second driving medium from said driving means to effect the stopping of said web at a predetermined line position, and a brake for concurrently stopping said driving means upon disengagement of said second driving medium.

10. In a tabulator of the class described, a plurality of feed drums for feeding a continuous web of paper past a printing position, a line spacing mechanism for rotating said drum to feed said web line by line, a cam actuated driving link under control of said tabulator for actuating said line space mechanism, a gear train associated with said line space mechanism, a pre-punched endless tape having therein groups of perforations, each group controlling the feeding functions for one form in said web of paper, said tape being fed by said gear train in synchronism with said web, means for sensing the perforations in said tape, a continuously running motor, a solenoid under control of said sensing means for rocking said motor into engagement with said gear train to effect a long feed of said web, a sec-

ond solenoid under control of said sensing means for rocking said motor out of engagement with said gear train to effect the stopping of said web at a predetermined line position, and a brake for concurrently stopping said gear train upon disengagement of said motor.

11. In a tabulator of the class described, a plurality of feed drums for feeding a continuous web of paper past a printing position, a line spacing mechanism for rotating said drums to feed said web line by line, a gear train associated with said line space mechanism, a pre-punched control tape fed by said gear train in synchronism with said web, means for sensing the perforations in said control tape, a continuously running motor, a "go" solenoid under control of said tape, a circuit to said "go" solenoid under control of said sensing means for rocking said motor into engagement with said gear train to effect a long feed of said web, a "stop" solenoid under control of said tape, and a second circuit to said "stop" solenoid under control of said sensing means for rocking said motor out of engagement with said gear train to effect the stopping of said web at a predetermined position.

12. In a machine of the class described, the combination of means for feeding a continuous web of paper, a current conducting drum rotatable by said feeding means and in synchronism with said web, an endless control tape adapted to be driven by said conducting drum, said control tape having a plurality of perforations arranged in predetermined relation to said web, means for sensing the perforations in said control tape, a "go" solenoid under control of said tape, a circuit to said "go" solenoid from said sensing means for rendering said feeding means effective, a "stop" solenoid under control of said tape, a second circuit to said "stop" solenoid from said sensing means for rendering said feeding means ineffective, a relay including a break contact disposed in said second circuit, a third circuit to said relay from said sensing means to open said break contact for rendering said second circuit ineffective, said relay also including a make contact, and a fourth circuit from said sensing means through said make contact to said "stop" solenoid for rendering said feeding means ineffective.

13. In a machine of the class described, means for feeding a continuous web of paper past a printing position, a continuously running motor, paper feeding means, a worm and worm wheel combination for driving said paper feeding means, a current conducting drum rotatable by said feeding means and in synchronism with said web, an endless control tape adapted to be driven by said conducting drum, said control tape having a plurality of perforations arranged in predetermined relation to said web, means for sensing the perforations in said control tape, a "go" solenoid under control of said tape, a circuit to said "go" solenoid from said sensing means for engaging said worm and worm wheel, a "stop" solenoid under control of said tape, a second circuit to said "stop" solenoid from said sensing means for disengaging said worm and worm wheel, a relay including a contact disposed in said second circuit, and a third circuit to said relay from said sensing means to open said contact for rendering said second circuit ineffective.

14. In a machine of the class described, the combination of means for feeding a continuous web of paper, a current conducting drum rotatable by said feeding means and in synchronism with said web, an endless control tape adapted

to be driven by said conducting drum, said control tape having a plurality of perforations arranged in predetermined relation to said web, means for sensing the perforations in said control tape, a "go" solenoid under control of said tape, a circuit to said "go" solenoid from said sensing means for rendering said feeding means effective, a "stop" solenoid under control of said tape, a second circuit to said "stop" solenoid from said sensing means for rendering said feeding means ineffective, a relay including a contact disposed in said second circuit, and a third circuit to said relay from said sensing means to open said contact for rendering said second circuit ineffective.

15. In a tabulator, a line spacing mechanism for feeding a web of paper line by line, a continuously running motor, a worm on the shaft of said motor, a worm wheel operatively associated with said worm and connected to said line spacing mechanism, a solenoid for operatively engaging said worm and worm wheel to feed the

web, and a plurality of circuits for said solenoid including a group of contacts controlled by a perforated tape and a second group of contacts actuated by functions of said tabulator, said circuits containing a pair of relays interacting in accordance with both of said groups of contacts to operate said solenoid to control the feeding of said web in variable amounts other than the amount fed by said line spacing mechanism.
